UNITED STATES PATENT OFFICE.

THEODOR RALL, OF CHICAGO, ILLINOIS.

VERTICAL-LIFT BRIDGE.

1,140,316.

Specification of Letters Patent. Patented May 18, 1915.

Application filed May 19, 1913. Serial No. 768,551.

To all whom it may concern:

Be it known that I, THEODOR RALL, a citizen of the United States, residing at Chicago, in the county of Cook and State of Illinois, have invented certain new and useful Improvements in Vertical-Lift Bridges, of which the following is a specification.

My invention relates in general to movable bridges, and more particularly to vertically lifting bridge spans.

The primary object of my invention is to provide a vertically movable bridge span with simple, efficient means for counterbalancing the weight of the span and compensating for the expansion and contraction of the span, due to changes in temperature.

A further object of my invention is to provide a vertical lift bridge which will be simple in construction, efficient in operation, and convenient in use.

My invention will be more fully disclosed hereinafter with reference to the accompanying drawings, in which the same is illustrated as embodied in several convenient practical forms, and in which—

Figure 1 is a side elevational view; Fig. 2 a plan view of the embodiment of the invention shown in Fig. 1; Fig. 3 a view similar to Fig. 1, showing a modified form of my invention; and Fig. 4 a view similar to Fig. 1 showing still another form of my invention.

Similar reference characters are used to designate similar parts in the several figures of the drawings.

Reference letters A and B designate stationary approach spans, between which is located a vertically movable span E. The approach and movable spans may be of any suitable construction, such, for instance, as trussed bridge spans.

C, D designate piers upon which the ends of the stationary spans A and B, respectively, are permanently supported, and upon which the ends of the movable span E normally rest.

G and H designate levers in the form of trussed girders, which are pivotally fulcrumed at g and h, respectively, upon tower posts N and O mounted directly upon the piers C and D and secured to the adjacent stationary spans A and B. Each of the levers G and H is provided with a weight K to counterbalance the weight of the vertically movable span. The end of each of these levers, opposite to the end on which

the counterbalance K is mounted, is provided with a roller L, which engages beneath a track M fixed to the upper chord F of the vertically movable span.

It will be understood by reference to Fig. 2 that the lifting levers G and H, and the parts coöperating with them, are arranged in pairs, one pair being located at each end of the movable bridge span.

Any suitable mechanism may be provided for raising and lowering the span E, such mechanism being shown as comprising a longitudinal shaft P journaled upon the lifting span E and provided with pinions p fixed to its opposite ends, which mesh with racks n secured to the vertical posts N and O. Any suitable arrangement of shafts and gears may be provided for rotating the shaft P, such, for instance, as a vertical shaft Q mounted upon the movable span E and operatively connected at one end by meshed bevel gears q with the shaft P, and its other end by meshed bevel gears r with a power shaft R, which may be rotated by any suitable motive power, such, for instance, as electricity or steam, or by hand.

The operation of my improved lifting bridge, as illustrated in Figs. 1 and 2, is as follows: When it is desired to lift the span E, the shaft P is rotated, which causes the pinions p, through engagement with the fixed racks n, to travel upwardly thereby raising the span E between the posts N and O. The weights K on the outer ends of the lifting levers G and H counterbalance the weight of the span E during its vertical movement.

During the upward movement of the span the supporting rollers L have paths of movement in the arcs indicated in dotted lines in Fig. 1, owing to the lifting levers being pivoted at g and h, respectively, upon the tower posts. During the lifting of the movable span the rollers L on the inner ends of the levers roll inwardly along the tracks M until the rollers lie in the horizontal plane of the fulcrums g and h of the lifting levers,

and during the remaining lifting of the span the rollers move outwardly relatively to the tracks M, which they engage, and through which they transmit the lifting power of the levers. In order to lower the span it is merely necessary to reverse the direction of rotation of the shaft P.

In the form of my invention illustrated in Figs. 1 and 2, the horizontal distance between the fulcrum of each lifting lever and

the point at which such lever engages the span through the medium of the roller automatically varies to compensate for the pivotal movement of the levers during the vertical lifting of the span, by reason of the rollers traveling inwardly and then outwardly relatively to the tracks which they engage on the span.

In Fig. 3 I have illustrated another embodiment of my invention, in which the pivotal movement of the levers during the vertical movement of the span is compensated by providing the levers with rolling fulcrums. Referring to Fig. 3, reference characters A' and B' designate stationary tower posts at the opposite ends of the vertically movable span E', such tower posts being mounted upon the piers C' and D', respectively. G' and H' designate the lifting levers, each of which is provided with a counterbalancing weight K' at its outer end, while its inner end is pivotally connected at L' to the upper chord F' of the span E'. The fulcrums of the levers G' and H' consist of rollers g' and h', respectively, which rest upon tracks a' and b' on the tops of the tower posts A' and B'. The means for raising and lowering the span in the form of my invention shown in Fig. 3 may be the same as above described in connection with Figs. 1 and 2, or any other suitable lifting mechanism may be provided.

In the operation of the embodiment of my invention shown in Fig. 3 the fulcrums g' and h' of the lifting levers G' and H' roll outwardly until the pivotal connections L' of the lifting levers with the top chord of the span reach the horizontal plane of the fulcrums, after which the fulcrums roll inwardly, or toward each other, during the remaining lifting movement of the span.

In Fig. 4 I have illustrated still another embodiment of my invention, in which the pivotal movement of the lifting levers during the vertical movement of the span is compensated by providing merely one of the levers with a rolling fulcrum. In this figure reference characters A² and B² designate the tower posts mounted upon piers C² and D², respectively. E² designates the lifting span, which normally rests at its ends upon the adjacent piers. G² and H² designate the lifting levers, each of which is provided at its end with a weight K² for counterbalancing the span. The inner end of each of the lifting levers is pivotally connected at L² to the upper chord F² of the span E². The lever G² is pivotally fulcrumed at g² upon the top of the tower A², while the lever H² is provided with a rolling fulcrum h², which rests upon the track b² at the top of the tower B².

In the operation of the embodiment of my invention shown in Fig. 4, during the lifting of the span the fulcrum h² of the lever

H² shifts outwardly along the track b² until the pivotal connections L² of the lifting levers with the upper chord of the span reach the horizontal plane of the fulcrums of the levers, after which the fulcrum h² of the lever H² rolls inwardly during the remaining lifting of the span. It will be observed, by reference to Fig. 4, that in the form of my invention shown therein, the ends of the bridge are moved in arcs indicated in dotted lines, when the bridge is raised or lowered.

In the several forms of my invention herein illustrated and described, not only is the pivotal movement of the lifting levers during the raising and lowering of the span compensated for, but the expansion and contraction of the span is also compensated for through the shifting connections provided either between the levers and the span or between the levers and the tower posts upon which they are fulcrumed.

From the foregoing description it will be observed that I have invented an improved lifting bridge which may be vertically raised or lowered by means of pivotal levers, the pivotal movement of the levers during the vertical movement of the bridge span being compensated by means for varying the horizontal distance between the fulcrum points of the levers and the pivotal connections of the levers with the span. It will also be observed that in my improved mechanism for lifting bridge spans the expansion and contraction of the span is so compensated as to in no wise affect the efficient operation thereof.

I claim:—

1. In a bridge of the class described, the combination with a vertically movable span, of stationary supports at each end of said span, and counterbalance levers pivotally mounted upon said supports and pivotally connected directly with the opposite ends of said span, the pivotal connections of one of said levers comprising one fixed pivot and one pivot in freely movable engagement with a substantially horizontal track for automatically varying the horizontal distance between the fulcrum point of said lever and its point of pivotal connection with the adjacent end of the span to compensate for the pivotal movement of said lever during the vertical movement of said span.

2. In a bridge of the class described, the combination with a vertically movable span, of stationary supports at each end of said span, and counterbalance levers pivotally mounted upon said supports and pivotally connected directly with the opposite ends of said span, and the pivotal connections of each of said levers comprising one fixed pivot and one pivot in freely movable engagement with a substantially horizontal track for automatically varying the horizontal dis-

tance between the fulcrum point of each lever and its pivotal connection with the adjacent end of the span to compensate for the pivotal movement of the levers during 5 the vertical movement of the span.

3. In a bridge of the class described, the combination with a vertically movable span, of stationary supports at each end of said span, counterbalance levers pivotally mounted upon said supports, and means for pivotally connecting said levers directly with the opposite ends of said span, the means for pivotally connecting one of said levers with the adjacent end of the span consisting 10 of a pivot in freely movable engagement with a substantially horizontal track to compensate for the pivotal movement of said lever during the vertical movement of the span.

20 4. In a bridge of the class described, the combination with a vertically movable span, of stationary supports at each end of said span, counterbalance levers pivotally mounted upon said supports, substantially horizontal tracks upon the opposite ends of said span, and pivots on the ends of said levers in freely movable engagement with said substantially horizontal tracks, the point of pivotal connection between each of said levers and the adjacent end of the movable span to compensate for the pivotal movement of said levers during the vertical movement of the span.

25 5. In a bridge of the class described, the combination with a vertically movable span, of stationary supports at each end of said span, counterbalance levers pivotally mounted upon said supports and pivotally connected with the opposite ends of said span, 30 the pivotal connection between the end of one of said levers and the adjacent end of said span comprising a rolling bearing and a member engaged thereby whereby the horizontal distance between the fulcrum point of said lever and its connection with the span will automatically vary during the vertical movement of the span to compensate for the pivotal movement of said lever.

35 6. In a bridge of the class described, the combination with a vertically movable span, of stationary supports at each end of said span, counterbalance levers pivotally mounted upon said supports and pivotally connected with the opposite ends of said span, 40 the pivotal connection between the end of each of said levers and the adjacent end of said span comprising a rolling bearing and

a member engaged thereby, whereby the horizontal distance between the fulcrum points of the levers and their connections 45 with the span will automatically vary during the vertical movement of the span to compensate for the pivotal movement of said levers.

7. In a bridge of the class described, the combination with a vertically movable span, of stationary supports at each end of said span, counterbalance levers pivotally mounted upon said supports and pivotally connected directly with the opposite ends of 50 said span, the pivotal connection between the end of one of said levers and the adjacent end of said span comprising a track fixed to the span and a roller on the end of said lever engaging the track, whereby the 55 horizontal distance between the fulcrum point of said lever and its connection with the span will automatically vary during the vertical movement of the span to compensate for the pivotal movement of said lever.

8. In a bridge of the class described, the combination with a vertically movable span, of stationary supports at each end of said span, counterbalance levers pivotally mounted upon said supports and pivotally connected with the opposite ends of said span, 60 the pivotal connection between the end of each of said levers and the adjacent end of the span comprising a track fixed to the span and a roller on the end of the lever 65 engaging the track, whereby the horizontal distance between the fulcrum points of said levers and their connections with the span will automatically vary during the vertical movement of the span to compensate for the 70 pivotal movement of said levers.

9. In a bridge of the class described, the combination with a vertically movable span, of stationary supports at each end of said span, counterbalance levers pivotally mounted upon said supports and pivotally connected with the opposite ends of said span, 75 the pivotal connections of one of said levers comprising one fixed pivot and one pivot in freely movable engagement with a substantially horizontal track for compensating for the expansion and contraction of said span.

In testimony whereof, I have subscribed my name.

THEODOR RALL.
